UNITED STATES PATENT OFFICE.

SARAH E. COVINGTON, OF BELLEFONTAINE, OHIO.

LINER FOR TIRES.

1,088,543.

Specification of Letters Patent.

Patented Feb. 24, 1914.

Application filed November 13, 1913. Serial No. 800,818.

To all whom it may concern:

Be it known that I, SARAH E. COVINGTON, a citizen of the United States, residing at Bellefontaine, in the county of Logan and State of Ohio, have invented certain new and useful Improvements in Liners for Tires; and I do declare the following to be a full, clear, and exact description of the invention, such as will enable others skilled in the art to which it appertains to make and use the same.

This invention is an inner liner adapted to be laced around the inner tube of a tire of the pneumatic type; and the object of the same is to improve the construction of such a liner which is to be interposed between the casing and the tube. This object is carried out in the manner hereinafter described and claimed, and as shown in the drawings wherein—

Figure 1 is a side elevation of a liner involving this invention. Fig. 2 is an enlarged cross section through the liner laid out flat. Fig. 3 is a section through the liner in position between a tube and its casing. Fig. 4 is a plan view of a portion of the liner, viewed from the inside.

Ordinarily this liner is intended to be disposed between the casing C and the air tube T, although its use is not limited in that respect because it might be strapped around a casing if the latter were sufficiently small or it could be strapped around a single-tube tire such as is sometimes used on bicycles. In fact, if made in short sections it might be used as a repair shoe, as the manner in which it is fastened in place permits it to expand within limits. In the following specification, however, I will describe it as a liner whose function is to protect the rubber air tube T from perforation by a nail or other obstruction which might pass through the outer tire C.

The body of this lining is made of two members. The inner member is two-ply, its sheets 1 and 2 being of strong, smooth, closely-woven and impenetrable fabric, with a non-combustible sheet 3 of asbestos or the like between them, and the three thicknesses stitched together as at 4. The outer member 5 is made of substantially the same material as the sheets 1 and 2 excepting that it is thicker, one edge is laid over the three-ply liner member as at 6, and then carried around the side edge thereof as at 7, the two members being connected by parallel

lines 8 of stitching, and a row of eyelets 9 being passed through the members between said lines. The other edge of the outer member 5 is carried around the opposite edge of the inner member as at 17, secured thereto by two lines of stitching 18, and has a row of eyelets 19 between the lines; and the edge of the outer member beyond the innermost line of stitching is left free at 15 to constitute a flap. The edges of the device thus formed are adapted to be connected by straps, or preferably by a lacing as indicated at 20, the same passing through eyelets 9 and 19. In the manufacture of this device the outer member is made a little fuller than the inner member, both transversely and longitudinally of the tube, and therefore a space exists between said members as indicated in Fig. 3.

This liner is applied to an inner tube T by passing it around the same and lacing it as will be clearly understood, leaving the valve stem to project from the inner side of the tube at a point between the edges of the liner. The tube is then inserted in the casing C and the casing put on the wheel, and finally the tube is inflated by the usual or any well known process until it is tight within the inner section of the liner. The fact that the asbestos or non-combustible sheet is interposed between the two sheets 1 and 2 of the inner section renders this device non-inflammable. The fabric of which these sheets and the single and thicker sheet composing the outer member is made is treated to render it water-proof, heat-proof, sand-proof, blow-out-proof, and puncture-proof; but the details of the process by which it is so treated form no part of the present invention. As above suggested, this device might be placed around the outside of a single tube so that in effect it would form a casing therefor, or it might be cut into sections and used as a repair shoe. While I have shown eyelets and a lacing tape, it is obvious that the edges might be connected by other means without departing from the principle of the invention.

What is claimed as new is:

The herein described liner comprising an inner section made up of two plies of fabric with an anti-combustible sheet interposed and the three plies stitched together, an outer section overlying one edge of the inner section and connected therewith by two lines of stitching, its opposite edge being carried

around the other edge of the inner section and connected therewith by two lines of stitching and left free to constitute a flap, and attaching devices connecting said edges 5 and adapted to lace the liner around an inner tube.

In testimony whereof I have hereunto set

my hand in presence of two subscribing witnesses.

SARAH E. COVINGTON.
